UNITED STATES PATENT OFFICE

JOSEPH L. WALKER, OF BATON ROUGE, AND GEORGE D. ALEXIS, OF NEW ORLEANS,
LOUISIANA

STITCHER HEAD

Application filed May 20, 1924. Serial No. 714,600.

This invention relates to a stitcher head designed primarily for stapling together pieces of veneer, and other materials, the device operating to cut predetermined lengths 5 of wire from a strand supplied to the head, shape the length into a staple of the desired length, and drive and clinch it.

One of the objects of the invention is to provide a stitcher head, the parts of which 10 are so constructed and assembled that the legs of the formed staple will not become deflected or distorted during the stapling operation but will be driven positively through the material fed into the path thereof.

15 A further object is to provide a stitcher head, the hammer of which is not provided with projections likely to break off and render the structure useless.

20 A further object is to provide means whereby a staple of any length can be formed and driven by the stitcher head, this being permitted in view of a simple form of adjustment provided.

25 A further object is to provide a stitcher head which is simple and compact, occupies a minimum amount of space, and is capable of various adjustments whereby it is particularly adapted for use in stitching wood stock with wire.

30 With the foregoing and other objects in view which will appear as the description proceeds, the invention resides in the combination and arrangement of parts and in the details of construction hereinafter described and claimed, it being understood that changes 35 in the precise embodiment of the invention herein disclosed may be made within the scope of what is claimed without departing from the spirit of the invention.

40 In the accompanying drawings the preferred form of the invention has been shown.

In said drawings

Figure 1 is a front perspective view of the stitcher head viewed from one side thereof.

45 Fig. 2 is a similar view of the stitcher head viewed from the opposite side thereof.

Fig. 3 is a section on line 3—3, Fig. 2.

Fig. 4 is a section on line 4—4, Fig. 2.

Fig. 5 is a section on line 5—5, Fig. 2.

50 Figure 6 is a section on line 6—6, Figure 1.

Figure 7 is a section on line 7—7, Figure 6.

Figure 8 is a view similar to Figure 6 showing a wire in position between the plunger and the die.

55 Figure 9 is a view similar to Figure 8 showing the relative positions of the parts after the former has bent the wire over the die and come into contact with the work.

Figure 10 is a section on line 10—10, Figure 9.

60 Figure 11 is a view similar to Figure 9 showing the relative positions of the parts at the beginning of the driving operation by the plunger, the die having been withdrawn from the path of the staple.

65 Referring to the figures by characters of reference 1 designates the base plate of the stitcher head, this being provided, in the structure shown, with spaced superposed ribs 2 extending transversely upon the back face thereof and connected by a retaining plate 3. Thus there is provided an opening 4 for the reception of a supporting bracket not shown. Secured to the front face of the base plate 1 at the sides thereof are longitudinal guide 70 and retaining strips 5, the inner sides of which are beveled as at 6 so as to cooperate to provide a dovetail groove between the strips.

75 Seated between the lower portions of the strips 3 is the main block 7 of the head, this block being secured to the base plate 1 by screws 8 or any other suitable means.

80 An opening 9 preferably rectangular, is extended longitudinally through the block 7 and a longitudinal slot 10 communicates with this opening. In this slot is mounted a lever 11 fulcrumed as at 12 and provided, at its lower end, with an extension or die 13 adapted to move into and out of the opening 9. The block 7 has an extension 14 adapted to rest upon the veneer or other work to be stapled. The opening 9 is extended longitudinally of this extension 14 as shown particularly in Fig. 7.

85 Slidably mounted within the opening 9 is a former bar or plunger in the form of a tube 15 rectangular in cross section. This tube is extended some distance above the block 7 and the lower end of the tubular 90

bar or plunger has a short longitudinal slot 16. By referring particularly to Figures 1, 6 and 7 it will be noted that the die 13 extends under and in the path of a hammer rod 44 hereinafter specifically described and which is slidable within the tube 15. As the normal positions of the parts have been illustrated in Figures 1 and 7 it will be apparent that, in order to permit the die 13 to assume the position shown in Figure 1 one side portion of the tube 15 must be provided with a longitudinal slot registering with the lower portion of the slot 10 (see Figure 6), said slot permitting the tube 15 to move downwardly from the position shown in Figure 7 while the die 13 remains in the position shown in Figures 1 and 6. Said end of the plunger bar 15 is also cut away at one side of the slot 16 to receive the end of the die 13 which works in a plane intersecting the plane of slot 16. The upper end of the plunger 15 is fixedly connected to a cross head 17 slidably mounted between the guide strips 5. This cross head has a bracket 18 fastened thereto and extending laterally therefrom, there being a push lever 19 pivotally mounted in the bracket. A cam bar 20 is slidably engaged by the bracket and has an inclined shoulder 21 near its upper end adapted to be engaged by and to shift the upper arm of the push lever when the cross head is moved downwardly. A spring 22 engages lever 19 and bracket 18 and serves to hold the upper arm of the lever normally pressed against the cam bar. The lower portion of the cam bar is adjustably mounted between spaced angle plates 23 and 24. The base flanges of these plates are adapted to be secured to the body or main block 7 by means of bolts 25. As shown in Fig. 2 the plate 23 is formed with longitudinal slots 26 for the reception of screws 27 which engage the bar 20. By tightening these screws the bar can be held against movement relative to the plate 23 but by loosening them said bar can be adjusted longitudinally to any desired elevation.

Secured between the lower portions of the plates 23 and 24 are guide or spacing strips 28 and 29 between which is adjustably mounted a stationary cutter 30. This is adapted to be held against movement by a set screw 31 extending through the plate 24. The inner end of the cutter 30 is beveled in a plane extending longitudinally of the cutter head, as shown at 32 and a longitudinal groove 33 is formed in the upper face of the stationary cutter 30. A movable cutter bar 34 is slidable between the plates 23 and 24 and between the inner ends of the strip 28 and the wall of the block 7 as shown particularly in Figs. 6 and 7. The lower portion of this movable cutter bar is so shaped as to work close to the beveled end 65 of the stationary cutter 30. A wire receiving

slot 35 is formed within the block 7 in line with the groove 33 in the stationary cutter 30. This slot also aligns with the slot 16 in the former plunger 15. Obviously, therefore, a wire fed along the groove 33 will be free to enter the slots 35 and 16. A spring 36 is connected at one end to the plate 23 and bears at its other end in the movable cutter bar 34 so as to hold said bar normally elevated. The upper end of bar 34, as shown in Fig. 2, is normally engaged by the lower end of the push lever 19.

Slidably mounted between the upper end portions of the strips 5 is a head 37 adapted to be connected at 38 to an operating eccentric not shown. This head has a link 39 slidably connected to it at 40, there being a longitudinal slot 41 within the link 39 through which the connecting pin 42 extends. This link is fixedly attached to the cross head 17 and by providing it the cross head and the head 37 are allowed a limited relative movement.

A spring 43 constitutes a yielding connection between the head 37 and the cross head 17 and fixedly secured to the head 37 by means of set screws 45 or the like is the hammer rod 44 preferably rectangular in cross section and adapted to fit snugly within the former plunger 15 and to reciprocate relative thereto. A latch lever 46 is pivotally connected to the head 37 and is normally seated within a recess 47 in the cross head 17. This latch lever has a lug 48 and a spring 49 bears against the lever and serves to hold the lug 48 normally lapping cross head 17 so as to thrust thereagainst. The lower end of the latch lever is offset at an angle, as shown at 50. As shown particularly in Fig. 1 the former plunger 15 is provided on one side with a cam block 51 and this is so located as to engage the former lever 11 as hereinafter explained.

In using this stitcher head a strand of wire is fed along the groove 33 in the stationary cutter 30 and under the movable cutter bar 34 so as to extend longitudinally within the slot 35 and transversely under the hammer bar 44 and within the slotted portion 16 of the former plunger. The distance the wire is moved into the slot 35 regulates the length of one shank of the staple to be formed while the length of the other shank of the staple is controlled by the distance of the cutter bar 34 from the hammer bar 44. The feeding of the wire into the stitcher head and the distance the wire is moved into the slot 35 is all regulated by feeding mechanism provided for that purpose and which constitutes no part of the present invention, it being understood by those skilled in the art that such wire feeding mechanism can be adjusted to feed any amount of wire desired during each operation. While the wire is in this initial position the die 13 of the former lever 11 is extended transversely under the wire and in

the path of the plunger 15 and hammer bar 44. See Figures 1, 6, 8 and 9. The head 37 is adapted to be operated by an eccentric or other means not shown and when this head descends motion is transmitted therefrom, during the first portion of its downward movement, through latch lever 46 and lug 48 to the cross head 17. During this first portion of the downward movement the push lever 19 comes against the cam shoulder 21 of bar 20 and is shifted out of engagement with the cutter bar 34. It might be stated, however, that before this action takes place the cutter bar 34 is moved downwardly a sufficient distance to cooperate with the stationary cutter 30 to cut off a length of wire. As soon as push lever 19 is deflected by the cam bar the cutter bar 34 will spring up to its normal position. As the plunger bar 15 moves downwardly it will straddle the die 13 and during this operation the upper wall of the slot 16 therein comes against the length of wire supported above the die 13 and bends it downwardly over the die as shown in Figure 9. During this operation the block 51 comes into engagement with the upper arm of the form lever 11 so as to hold the die positively in position for shaping the wire. During the completion of this downward movement of the former plunger 15 the block 51 gradually moves downwardly out of engagement with the upper end of the former lever 11 and comes to position inwardly of the fulcrum 12. At this instant the end 50 of the latch lever 46 comes against the edge of block 7 so that the latch lever is deflected laterally out of engagement with the cross head 17. Consequently a positive thrust through the latch lever from the head 37 to the cross head 17 is stopped and further movement of the head 37 in a downward direction will result in placing spring 43 under increased tension and will result in yielding pressure of the plunger bar or former against the work W, as shown in Figures 9 and 10, and the continued downward movement of the hammer bar 44 relative to the plunger 15. This movement will be limited by the length of slot 41. During this downward movement of the bar 44 relative to plunger 15 the lower end of the bar will come against the crown portion of the formed staple S and as block 51 has wedged against the lower arm of lever 11 and swung the die 13 laterally, from under the formed staple, the hammer will be free to drive the staple downwardly into the work W provided therefor. During the return movement of the operating eccentric the parts will be brought back to their initial positions and another length of wire can be fed into the stitcher head after which the foregoing operation can be repeated.

Importance is attached to the fact that with this stitcher head staples of different lengths can be made and driven. This is done by

placing shims or spacing plates between the attaching flanges of the plates 23 and 24 and the block 7. In this way the cutters 34 and 30 can be spaced desired distances from the former plunger 15.

What is claimed is:—

1. In a stitcher the combination with a head and a cross head movably mounted, and a yielding connection therebetween, of a tubular former plunger movable with the cross head, a hammer bar movable with the head and slideable within the former plunger, a latch for transmitting thrust from the head to the cross member, a former die in the path of the plunger, said plunger and die cooperating during the movement of the head and cross head in one direction for shaping a wire upon the die, means operated by the plunger during the latter portion of its movement toward the die for shifting the die out of the path of the hammer bar, and means for automatically uncoupling the cross head from the thrust member, the head and hammer bar being movable independently of the uncoupled cross head and against the action of the yielding connection to drive the formed wire.

2. In a stitcher head the combination with a head and a cross head mounted for reciprocation, a latch for transmitting thrust from the head to the cross head, and a yielding spacing means between the head and the cross head, of a tubular plunger movable with the cross head, a hammer bar movable with the head and slideable within the plunger, a die movably supported normally in the path of the plunger, said plunger and die cooperating to shape a wire inserted therebetween, means operated by the plunger for shifting the die out of the path of the hammer bar, and means for shifting the latch to disengage the head from the cross head, said head being movable relative to the cross head and against the action of the yielding means to force the hammer bar against the shaped wire to drive it.

3. In a stitcher head the combination with a block having a feed slot therein, there being an opening intersecting the slot, a former plunger and a hammer bar mounted for reciprocation within the opening, and a movably mounted die normally projected into the path of the plunger bar, of a structure detachably connected to the block and shiftable relative thereto, a stationary cutter adjustably mounted within said structure, a movable cutter bar in said structure, a push lever movable with the former plunger, said lever normally engaging the end of the cutter bar, and means mounted on said structure for engagement with the push lever to disengage said lever from the movable cutter bar during the movement of the plunger in one direction.

4. The combination with a block having a feed slot therein and an opening intersect-

ing the slot, of a former plunger and a hammer bar mounted for reciprocation within the opening, a die movably mounted within the opening and normally positioned in the path of the plunger, a structure detachably connected to the block, a stationary cutter secured therein and having a longitudinal wire guiding groove, a movable cutter bar within said structure, yielding means for holding the movable cutter bar normally in one position, an adjustably mounted cam bar, and a push lever movable with the former plunger and normally engaging the movable cutter bar, said push lever and cam bar cooperating to disengage the lever from the cutter bar after a predetermined movement of the former plunger in one direction.

In testimony that we claim the foregoing as our own, we have hereto affixed our signatures.

JOSEPH L. WALKER.
GEORGE D. ALEXIS.
